UNITED STATES PATENT OFFICE.

FRANKLIN A. MORAND, OF CHEYENNE, AND JOSEPH EDWARDS, OF HAYS CITY, KANSAS.

CAR-COUPING.

SPECIFICATION forming part of Letters Patent No. 228,212, dated June 1, 1880.

Application filed September 24, 1879.

To all whom it may concern:

Be it known that we, FRANKLIN ALEXANDER MORAND, of Cheyenne, in the county of Osborne and State of Kansas, and JOSEPH EDWARDS, of Hays City, in the county of Ellis and State of Kansas, have invented a new and Improved Car-Coupling, of which the following is a specification.

Figure 1 is a plan view, partly in section, of our improved coupling. Fig. 2 is a vertical longitudinal section taken through the line x x , Fig. 1. Fig. 3 is a side elevation of the coupling-bar. Fig. 4 is a perspective view of the same. Fig. 5 is a detail view of a modified form of the coupling-rod.

Similar letters of reference indicate corresponding parts.

The object of this invention is to furnish a car-coupling so constructed as to couple the cars automatically as they are run together, couple cars of different heights, and connect the cars securely, while giving them the necessary play for passing around curves.

The invention consists, essentially, in a coupling-bar made in two parts and provided with a ball-and-socket joint at its rear end for giving it a free vertical and lateral movement, as hereinafter fully described.

A are the draw-bars, which are designed to be secured to the frame of the car. The bar B of the coupling is made in two parts or halves, placed the one upon the other. The inner ends of the parts of the coupling-bar B are placed between the ends of a U-shaped bar, C. The bar C is made wider than the end of the coupling-bar B, and its ends are connected together by two pins or bolts, c', passed through their corners at the opposite sides of the said bar B.

In the inner surfaces of the parts of the bar B are formed semicircular recesses b', to receive a ball, d', formed upon the forward end of a rod, D, which passes through the bend of the U-bar C, and has a pin or other fastening attached to it to prevent it from being drawn out. The draw-rod D also passes through holes in the center of two cross-bars, E, placed between the arms of the U-bar C, and the ends of which enter the slots of two metal plates, F, attached to the draw-bars A.

Upon the draw-rod D, between the cross-bars E, is placed a spiral spring, G. The ends of the spring G rest against the cross-bars E, so that it may prevent a too heavy jar when the cars are started and when they are run together.

The inner edges of the rear ends of the parts of the coupling-bar B are beveled, so that their forward ends may be separated without releasing the ball d' of the draw-rod D, and without spreading the ends of the U-bar C. In the forward end of the coupling-bar B is formed a semicircular or cup-shaped cavity or mouth, b², to guide the end of the coupling-rod H into place from whatever direction it may come.

The coupling-rod H has a ball, h', formed upon each end, which balls h' are tapered or made conical, so that they may readily enter the mouth of the coupling-bar B, spread the forward ends of its parts, and enter the cavities b³, formed in the adjacent sides of the said parts at a little distance from their forward ends, as shown in Fig. 2.

The coupling-rods H may be made with a ball, h', at one end, and an eye, h², at the other end, as shown in Fig. 5, to adapt them for use for coupling a car provided with our improved coupling to one provided with the ordinary link-and-pin coupling.

I is a U-bar, which passes around and is attached to the lower part of the coupling-bar B. The arms of the bar I project above the coupling-bar B, and to their ends are pivoted the upper corners of the locking-block J, the lower edge of which rests upon the upper side of the upper part of the coupling-bar B, to prevent the said part from rising and releasing the coupling-rod H.

The cars are uncoupled by swinging the locking-block J up out of contact with the coupling-bar B.

To the lower corners of the locking-block J are attached arms K, for convenience in operating it. The locking-block J, when turned up, rests against the draw-bar A in such a position as to be thrown down by the jar when the cars run together, so as to lock the coupling-rod in place automatically. The space within the draw-bar A is made so much larger than the coupling-bar B as to give the said

coupling-bar B the requisite lateral and vertical play, the ball-joint d' allowing it to move freely.

Having thus described our invention, what we claim as new, and desire to secure by Letters Patent, is—

1. The ball-and-socket joint b' d' at the rear end of the coupling-bar B, to give the said coupling-bar a free lateral and vertical movement, substantially as herein shown and described.

2. The coupling-bar B, made in two parts and provided with a ball-and-socket joint at its inner end, substantially as herein shown and described.

FRANKLIN A. MORAND.
JOSEPH EDWARDS.
